UMBRELLA HANDLE

David Miller, Lancaster, Pa.

Application July 8, 1952, Serial No. 20,511

Term of patent 14 years

(Cl. D88—3)

To all whom it may concern:

Be it known that I, David Miller, a citizen of the United States, residing at Lancaster, in the county of Lancaster and State of Pennsylvania, have invented a new, original, and ornamental Design for Umbrella Handle, of which the following is a specification, reference being had to the accompanying drawing, forming a part thereof.

Fig. 1 is a front elevational view of the umbrella handle embodying my design;

Fig. 2 is a side elevational view thereof;

Fig. 3 is a rear elevational view thereof; and

Fig. 4 is a top plan view thereof.

I claim:

The ornamental design for an umbrella handle, as shown.

D. MILLER.
